UNITED STATES PATENT OFFICE.

HULDREICH KELLER, OF BERLIN, GERMANY, ASSIGNOR TO GENERAL ELECTRIC COMPANY, A CORPORATION OF NEW YORK.

CENTRIFUGAL COMPRESSOR AND PUMP.

987,994.

Specification of Letters Patent: Patented Mar. 28, 1911.

Application filed June 21, 1907. Serial No. 380,052.

To all whom it may concern:

Be it known that I, HULDREICH KELLER, a citizen of Switzerland, residing at Berlin, Germany, have invented certain new and 5 useful Improvements in Centrifugal Compressors and Pumps, of which the following is a specification.

The present invention relates to that type 10 in the impeller is arranged to discharge relatively small jets or streams of liquid, which liquid enters a surrounding conducting apparatus as small pistons between which the air or other gas undergoing compression is 15 confined.

The prior constructions with which I am 20 familiar are open to the objection that the conducting channels in the stationary member are either too wide at their points of 25 exit or they have a curved formation. Both of these characteristics are objectionable in that they greatly reduce the efficiency of the apparatus. The constructor in broadening the channels in the stationary member, relying 30 upon the familiar form in centrifugal water pumps, overlooked the fact that he was dealing with a compressible fluid and disregarded the fact that in centrifugal air pumps the volume of fluid medium passing 35 through said channels is greatly reduced. Even the channels which have a constant cross-sectional area from the entrance to the exit result in a loss of efficiency. For example, assume a conduit or channel having a 40 uniform cross-section and the air compressed from 97% vacuum to atmospheric pressure, its volume will be decreased to about one-thirtieth. If the water pistons were initially separated by a distance of 60 millimeters, 45 this distance will decrease as the pistons move away from the point of entrance due to the uniform cross-section of the channel or conduit until they are separated by an amount equal to 60 divided by 30 or 2 milli- 50 meters. In fact, the pistons will contact with each other at some point in the channel. If the walls of the channel are curved each water piston as it passes therethrough will, on account of its great centrifugal force, fol- 55 low the concave wall of the channel and leave a space between it and the convex wall, thus permitting the air which has been compressed to expand again and also to retreat from the exit.

55 For illustration I have specifically mentioned the disadvantages of a pump having

a conducting member with channels of uniform cross-section, but it is to be understood that they are even greater with channels which expand toward the point of discharge. 60

The purpose of my invention is to avoid the objections above set forth and to provide a centrifugal compressor and pump of improved construction and one having a high 65 efficiency in operation.

In the accompanying drawing, which 70 illustrates one of the embodiments of my invention, Figure 1 is a view partially in section, of an impeller and the surrounding annular member containing the directing channels; and Fig. 2 is an axial section of the same.

1 indicates the main shaft upon which the 75 impeller is mounted, the latter comprising a hub having a flange 2 extending perpendicular to the axis and buckets or vanes 3 and a cover 4. Between the vanes are channels 5 that rapidly decrease in cross-sectional area 80 from the entrance to the point of discharge of the periphery. The vanes are so shaped as to cause this reduction in area. The vanes are made as sharp as possible at the receiving ends and are made smooth so as to avoid losses of all kinds in so far as it is possible. 85 The water leaving the impeller will be in the form of thin streams or jets, the continuity of which is interrupted by the walls or partitions of the surrounding member 6 as the impeller rotates. This results in 90 the formation of a series of small water pistons which pass through the channels in said member 6 and in so doing carry air or other gas picked up by them as they cross the gap between the stationary and revolving 95 parts.

In the annular stationary member 6 which 100 is made in the form of a double ring is a plurality of rectilinear channels 8. Between the two rings 9 and 10 are located V-shaped 105 partitions 11 which are thin at their inner ends and widen rapidly toward the periphery. The channels formed between the partitions gradually decrease in width from the point of entrance 12 to the point of discharge or exit 13, as shown in Fig. 1, the side walls of the channels being plane surfaces that converge toward said exit. In other words, the channels decrease in cross-sectional area measured in a plane perpendicular to the axis. The channels may also decrease in cross-sectional area in a plane 110

parallel to the axis, as shown in Fig. 2. The opposed walls of the partitions are straight and the center line of the channels is substantially tangential to the impeller. 5 By comparing the two figures of the drawing, the marked decrease in cross-sectional area of the channel can be observed. The linear width of the channels decreases one half from the entrance to the exit, and the 10 axial width by such an amount that the cross-sectional area of each channel at the exit is only one-fourth that of the entrance; but the invention is not limited to these dimensions or proportions. If for example 15 there is a decrease in the volume of air in these channels to one-thirtieth of the initial, and the water pistons are initially separated by 60 millimeters, then they will approach each other by about one-seventh 20 the total distance or to about 9 millimeters, as contrasted with 2 millimeters, previously referred to. Further, the water pistons will be about four times as thick at the exit 25 as they were at the entrance, and by reason of this fact are well adapted to resist unilateral excess pressure. In order to obtain greater compression of the air, the decrease 30 in cross-sectional area of the channels toward the point of exit is made larger. Owing to the character of the channels and 35 the water pistons, all danger of the pistons breaking through is prevented.

In Fig. 1 the shaded parts 14 represent the bodies or pistons of water between which 35 are caught or trapped the air pistons 15. It will be observed that the length of the air pistons decreases from the center of the 40 annular member outward, due to the fact that they are conpressed to a greater or less extent.

In some cases it will be found desirable to slightly enlarge the channels at the points of exit as shown at 16 in order to cause a 45 more gentle passage of the water into the inclosing casing.

The impeller and the water and air or other gas-discharging member are mounted in a suitable casing having a conduit admitting water or other liquid to the center of 50 the impeller, and a conduit for conveying air or other gas to the region between the relatively rotating parts of the apparatus. Conduit means is provided for conveying off the gas and liquid issuing from the 55 stationary member.

In accordance with the provisions of the patent statutes, I have described the principle of operation of my invention, together with the apparatus which I now consider 60 to represent the best embodiment thereof; but I desire to have it understood that the apparatus shown is only illustrative, and

that the invention can be carried out by other means.

What I claim as new and desire to secure 65 by Letters Patent of the United States, is,—

1. In an apparatus of the character described, the combination of an impeller which discharges liquid in jets or streams, a member which surrounds the impeller, and 70 rectilinear channels in the said member whose cross-sectional areas decrease toward the points of discharge.

2. In an apparatus of the character described, 75 the combination of an impeller which discharges liquid in jets or streams, a member which surrounds the impeller, and rectilinear channels or passages in said member, the center lines of said channels extending substantially tangential to the periphery of the impeller and the side walls of each channel being plane surfaces that converge toward its exit so that the cross-sectional area of the channel decreases from 80 its entrance to its exit.

3. In an apparatus of the character described, 85 the combination of an impeller which discharges liquid in jets or streams, an annulus which surrounds the impeller, and straight channels formed in the annulus for receiving liquid and gas and discharging them outwardly, each of said channels decreasing in width toward the point of discharge measured in an axial plane and decreasing in thickness toward the point of 90 discharge measured in a plane perpendicular to the axis.

4. In an apparatus of the character described, 95 the combination of an impeller which discharges liquid in jets or streams, a member which surrounds the impeller, and rectilinear channels in the said member whose cross-sectional areas decrease toward the points of discharge and are slightly enlarged at their ends to decrease the disturbance due to the liquid entering the inclosing casing.

5. In a centrifugal pump for compressing elastic fluids, the combination of an impeller with a surrounding conveying agent having 100 channels therein whose middle axis is substantially straight and through which the compressing liquid is discharged in individual slender jets, each channel being substantially rectilinear for the greater portion 105 of its length and decreasing in cross-sectional area toward the exit by an amount causing compression of the elastic fluid.

In witness whereof, I have hereunto set my hand this 24th day of May, 1907.

HULDREICH KELLER.
